L. J. WAHL

CLIPPER

Filed April 7, 1924

Fig. 1

UNITED STATES PATENT OFFICE.

LEO J. WAHL, OF STERLING, ILLINOIS.

CLIPPER.

Application filed April 7, 1924. Serial No. 704,701.

To all whom it may concern:

Be it known that I, LEO J. WAHL, a citizen of the United States, residing at Sterling, in the county of Whiteside and State 5 of Illinois, have invented a certain new and useful Improvement in Clippers, of which the following is a full, clear, concise, and exact description, reference being had to the accompanying drawings, forming a part of 10 this specification.

My invention relates to clippers and more particularly to a clipper of the vibratory type.

It is a purpose of my invention to provide 15 an electromagnetically operated vibratory clipper that is so constructed that the same will have a minimum width at the portion thereof that is to be gripped by the hand of the operator and to provide such 20 a clipper that has the metal in the magnet core and the armature so arranged as to provide a better path for the magnetic flux than has been previously the case.

It is a further purpose of the invention 25 to provide a flexibly mounted armature that is constructed so as to obtain the greatest thickness of metal in the lines of magnetic flux and to further so join the armature with the flexible mounting therefor that the resiliency 30 of the mounting is not impaired by the joint and stiffness in the armature is obtained where this is the most desirable.

It is still a further purpose of the invention to so construct the armature in 35 an electro-magnetically operated clipper as to obtain the greatest amount of stiffness for said armature for a given amount of weight and also obtain a more efficient action between the electromagnet and the armature 40 by shaping the armature so that the lines of force act substantially straight across between the armature and the central core of the electro-magnet.

Other objects and advantages of the invention 45 will appear as the description of the accompanying drawings proceeds. However, I desire to have it distinctly understood that I do not intend to limit myself to the exact details shown or described but 50 that I intend to include as part of my invention all such obvious changes and modifications of parts as would occur to a person skilled in this art and as would fall within the scope of the claims.

55 In the drawings:

Fig. 1 is a view partly in vertical section

and partly in elevation of my improved clipper;

Fig. 2 is a plan view thereof showing the major portion of the cover broken away; 60

Fig. 3 is a section taken on the line 3—3 of Fig. 2;

Fig. 4 is a section taken on the line 4—4 of Fig. 1;

Fig. 5 is a plan view of one of the laminations of said coil; and 65

Fig. 6 is a similar view of another lamination.

Referring in detail to the drawings, the clipper comprises a casing having a main 70 body portion 10 and a cover 11, the cover being held in place on the main body portion 10 by means of any suitable fastening devices such as those indicated by the numeral 12 in Fig. 2. The main body portion 10 of the clipper is provided with a pair of 75 upwardly extending lugs or bosses 13 for supporting the electro-magnet comprising the coil 14 which is wound on a core comprising a central main core portion 15, a 80 longitudinally extending portion 16 which is provided with a pair of legs or branches 17 extending in opposite directions from the main core portion 15 and at right angles thereto, said branches 17 terminating in 85 right angular end portions 18 extending substantially parallel to the portion 15. The longitudinally extending portion 16, it will be noted, is quite narrow and the right angular end portions 18 are widened so as 90 to provide a greater amount of material in the portions of the core where it is desirable to provide an easy path for the lines of magnetic force and further making it possible to reduce the width of the body portion 95 10 between the side walls 19 by having the reduced portions 16 located between the coil 14 and one of said walls 19. The widened right angularly extending end portions 18 are further provided so as to provide 100 suitable fastening means for the coil and core.

It will be noted that the lugs 13 are offset inwardly from the side 19 and that the fastening devices 20 that pass through the 105 portions 18 of the core and the bosses or lugs 13 are located inwardly from the end of the coil 14 being located on opposite sides of the coil instead of beyond the end thereof, thus making the casing for the clipper 110 but very little wider than the length of the coil 14 necessitates.

The clipper is provided with a stationary blade 21 and with a movable blade 22 the construction of these parts not forming a part of the present invention. The movable 5 blade 22 is actuated by a vibratory armature that is actuated by the electro-magnet comprising the coil 14 said coil 14 being supplied with alternating current from any suitable source through the conductors 23. 10 The movable blade 22 is connected with the vibratory armature 24 by means of the connecting arm 25 which is secured in any suitable manner to the blade 22 so as to provide a yielding connection between said 15 blade and member 25.

The armature 24 is provided with a resilient mounting comprising the resilient member 26. A suitable projection 27 extends from one side of the casing 10 and 20 upwardly from the bottom thereof. The projection has a depression 28 therein upon which rests the bar 29 which extends toward the member 26 and is provided with a reduced end portion 30 entering an opening 25 31 in the member 26 and serving as a bearing for one side thereof. A screw 32 is provided for adjusting the position of the member 29 vertically. A bolt 42 is also provided at the thickened rear end portion 30 35 43 of the body portion 10 which enters a suitable opening in the rear end of the member 26, said bolt having a nut 44 engaging the member 26 to clamp the same in position. An adjusting screw 45 is further provided for adjusting the spring 26 and armature 24 crosswise of the device.

In order that the joint between the armature 24 and the spring 26 does not interfere with the resiliency of the member 26 and the 40 tuning thereof by grinding the same away, as indicated at 33, the resilient member 26 is provided with a right angular end portion 34 and the armature 24 is provided with a right angular end portion 35, said right 45 angular ends being secured together in any suitable manner as by means of the fastening members 36. The members 34 and 35 are joined together substantially in alignment with the thickened end 18 of the 50 core, thus providing the greatest amount of metal in the path of the lines of magnetic force. Further, the provision of the joint in the manner shown in Fig. 2 provides an absolutely stiff joint at the bend or off-set 55 between the armature 24 and the resilient member 26. Thus, any adjustment of the spring member 26 will also accurately adjust the member 25 and the blade 22, and further, the spacing of the armature 24 relative to the core 15 will be positively maintained by adjustment of the screw 32, as no bending will take place at the off-set between the member 26 and the member 24. The joint between the member 25 and the 60 65 armature 24 is made in a similar manner,

the member 25 having a right angular end portion 37 which is secured flatwise against the end 38 of the armature 24 by means of any suitable fastening means such as the rivet 39. The joint made between the members 24 and 25 at 37 and 38 also places the greater amount of metal available due to said joint substantially in alignment with the thickened end portion 18 of the pole piece. 75

In order to stiffen the armature 24 the same is preferably shaped as shown in Fig. 3, the central portion thereof being off-set as indicated at 40 toward the electromagnet 14. The width of the off-set portion 40 is substantially the same as the thickness of the central core member 15 and, accordingly, the lines of force, which are indicated at 41 in Fig. 3, will be substantially straight between said core 15 and the armature 24 85 as practically all the magnetic flux will occur between the off-set portion 40 and the core member 15.

By placing the joint between the spring 26 and the armature 24, as indicated in Fig. 2, the maximum length of the spring 26 is obtained as the joint does not in any way affect the resiliency of the spring. Stiffness is provided at the joint where this is desired and a greater amount of iron is placed in the magnetic field than if the joint were elsewhere. By providing the armature with the central off-set portion, the same is made much stiffer for a given weight of material and due to the action of the lines of force substantially in straight lines between the core and the armature, a quicker action of the electromagnet is obtained. 95 100

It will be noted upon reference to Fig. 2 that the portion 15 of the core is comparatively wide and the portion 16 is much narrower. However, upon reference to Fig. 4, it will be seen that the portion 15 of the core is comparatively thin and the portion 16 much thicker. Thus, the required cross section for the core is obtained in the portion 16 without unnecessarily widening the same, whereby a narrow casing can be provided making it easy for the operator to hold the device in his hand. 110 115 120

The coil is laminated as will be clear from Figs. 1 and 4 and the greater thickness is obtained by providing the laminations 50 having the arms 51 on the ends thereof on opposite sides of the laminations 52 having the arms 53 and the central arm 54 passing through the coil 14.

Having thus described my invention what I desire to claim and secure by United States Letters Patent is:

1. In a device of the character described, a vibratory member comprising an armature, a resilient member secured to one end of said armature and an arm secured to the other end of said armature, said vibratory

member being offset between the ends thereof, the joint between said armature and said resilient member lying in one of the offsets to stiffen the same.

5. 2. In a device of the character described, a vibratory member comprising an armature, a resilient member secured to one end of said armature and an arm secured to the other end of said armature, said vibratory member being offset between the ends thereof, the joint between said armature and said arm lying in one of the offsets to stiffen the same.

3. In a device of the character described, 15 an electro-magnet having a coil and core, said core having branches lying on opposite sides of said coil, a vibratory member comprising an armature, a resilient member secured to one end of said armature and an 20 arm secured to the other end of said armature, said vibratory member being offset between the ends thereof, the joint between said armature and said resilient member lying in one of the offsets to stiffen the same 25 and in alignment with one of said branches to increase the amount of iron in the field of said magnet.

4. In a device of the character described, 30 an electro-magnet having a coil and a core having a central portion extending through said coil and branches extending on opposite sides of said coil and a vibratory member comprising an armature having a right an-

gular end portion and a resilient member having a right angular end secured face to face to the right angular end of said armature to thicken said vibratory member substantially in alignment with one of the branches of said core.

5. In a device of the character described, 40 an electro-magnet having a coil and a core having a central portion extending through said coil and branches extending on opposite sides of said coil and a vibratory member comprising an armature having a right angular end portion and a resilient member having a right angular end secured face to face to the right angular end of said armature to thicken said vibratory member substantially in alignment with one of the 45 branches of said core, said vibratory member being offset intermediate the ends thereof to accommodate said coil.

6. In a device of the character described, 55 a casing, an electro-magnet in said casing comprising a coil, a core in said coil having branches extending transversely rearwardly of said coil and having portions extending on opposite sides of said coil and a vibratory member comprising an armature having 60 portions extending on opposite sides of said coil toward the branches of said core and substantially in transverse alignment therewith.

In witness whereof, I hereunto subscribe my name this 26th day of March, A. D. 1924.

LEO J. WAHL.
